UNITED STATES PATENT OFFICE.

FRANK J. TRAN AND FRANK CAIS, OF CLEVELAND, OHIO.

WORKMAN'S TIME-RECORDER.

1,184,277.

Specification of Letters Patent. Patented May 23, 1916.

Application filed March 23, 1910. Serial No. 551,163.

To all whom it may concern:

Be it known that we, FRANK J. TRAN and FRANK CAIS, citizens of the United States, and residents of Cleveland, county of Cuyahoga, and State of Ohio, have jointly invented a new and useful Improvement in Workmen's Time-Recorders, of which the following is a specification, the principle of the invention being herein explained and 10 the best mode in which we have contemplated applying that principle, so as to distinguish it from other inventions.

The present invention relating as indicated to workmen's time recorders, has regard more particularly to certain improvements in workmen's time recorders of the type described in U. S. Patents Nos. 875,392 and 875,393.

One of the objects of the present improvements is to avoid the difficulty of registering more than once on the same portion of the record sheet, no matter how closely together successive operations of the machine may occur.

25 Ordinarily in recorders of the class in hand, provision is made for a relative shifting of the time-printing device and platen at stated intervals only. As a result, should a workman by accident, or otherwise, take 30 occasion to operate the register twice within any period thus marked off for the reception of his record, the second imprint will be made directly over the first, thus obscuring such first record and leading to much confusion. It is, moreover, oftentimes desirable to have on occasion, a more frequent registration of the goings and comings of 35 certain workmen than of others, so that while a relative shifting of the platen and 40 printing device for "in" and "out" for morning and noon, and again for afternoon and evening, will suffice in some cases, a more frequent record in other cases is desired.

The means whereby the foregoing results 45 may be readily and easily accomplished in the type of recorder in hand, will herein-after be fully described and particularly pointed out in the claims.

The annexed drawing and the following 50 description set forth in detail certain mechanism embodying the invention, such disclosed means constituting, however, but one of various mechanical forms in which the principle of the invention may be used.

55 In said annexed drawings:—Figure 1 is

a broken front elevation of a time recorder of the kind referred to above, wherein have been embodied our present improvements; Fig. 2 is a central longitudinal section of such recorder on the line 2—2, Fig. 1; Fig. 60 3 is an enlarged sectional view of a detail of the recorder; Figs. 3, 4 and 5 are similar views of such detail but showing the parts in different operative positions; and Fig. 65 6 shows a modification in the construction of such detail.

The general construction and mode of operation of the recorder will need to be only briefly noted. Such recorder, then, comprises a case A, within which is revolvably 70 mounted a drum or platen B, shown in section in Fig. 2. To this drum is affixed the record sheet, which is divided, as will readily be understood, into a series of transverse spaces corresponding with individuals who 75 are to use the recorder, and these in turn by a series of vertical lines into spaces corresponding to periods of time, as, for instance, days. The number of days, in case the later period be selected, will obviously 80 vary with the use to which the machine is to be put, and corresponding changes may require to be made in its size. Transversely movable across the platen on ways a in the upper part of the case, is supported a time- 85 printing device C, which is shifted at stated intervals so as to be positioned over those portions of the sheet on the platen corresponding with successive periods of time. Such operation of the time-printing device 90 is had through a clock-actuated spindle c parallel with said ways. The same clock C that operates such spindle, serves also to rotate another parallel shaft c' that carries a series of pins or stops c² whereby movement of the time-printing device is controlled, such movement being induced by a suitable counter-weight c³ or like means. Rotation of shaft c' by bringing successive pins c² into a stated position with respect 95 to an arm on the time-printing device C, permits the latter to pass until it is stopped by the next pin.

As in the recorder described in Patent No. 875,393, we propose to use a dial A' provided with figures or designating characters a², such characters corresponding with transverse portions of the platen, appropriated, as has just been stated, to the use of individual workmen. Preferably these 100 105 110

characters are arranged in two semi-circular series as shown. For rotating the platen two levers *b* are provided in front of said dial, associated with which are pointers *b'* of unequal lengths, the series of characters just referred to being so arranged as to be indicated by the longer and the shorter of said two pointers respectively. When a pointer is then brought into position with respect to any particular character, and the lever pressed inwardly, a reciprocable shaft *b²*, Fig. 2, lying in the hollow drum-shaft *b³* will be actuated inwardly and by suitable connections *b⁴* cause the time-printing device to contact with the transverse portion of the platen corresponding with the character indicated, and at a point longitudinally of such portion depending on the position of the device relatively to the platen.

20 In the present improved construction of the recorder, we provide for reversibly rotating the platen by rotation of the levers *b* thus provided in front of the dial of the case, interposing, with this in view, a set of three bevel gears *b⁵*. As clearly shown in Fig. 2, these gears are held in a rectangular bracket *a³* secured to the front wall of the case and the stem or short shaft *b⁶* that carries the levers is extended within the tubular somewhat larger shaft that carries the platen so as to afford an ample bearing for the former, and insure as rigid a connection as though the two shafts were continuous. By reason of such reversible rotation of the platen it will follow that either lever may be brought into different positions with respect to the end of the drum, and thus be adapted to coöperate with the latter at various selected points about its circumference. By the use of the gears between the levers and the platen, the transverse spaces on the platen do not have to be of the same size as the distances between the characters on the dial *A'* but may be made of any convenient size. The gears also allow the platen to be spaced accurately to correspond with the characters on the dial, as will be readily seen.

50 In the preceding forms of recorder to which reference has been made, the outer ends of the levers *b* have been respectively provided with pins or plungers adapted to coöperate with shallow holes or recesses in the dial. Such engagement of the pins and apertures being used simply to insure correct location of the parts, the pins were resiliently mounted so as not to interfere with the full inward movement of the lever. In the present construction, instead of having such pins or plungers (designated by reference letter *b⁷*), resiliently mounted, we attach the same fixedly to the levers and extend the apertures *a⁴* wherewith they are optionally registrable through the front wall of the case so that upon the inward

movement of a lever, the corresponding pin is caused to project within the case a definite distance. Attached to the forward end of the drum so as to lie adjacent to the series of apertures *a⁴* through which the pins 70 on the levers may be thus caused to project, are a series of adjustable stop devices *D*, the construction of which is shown in detail in Figs. 3, 4 and 5. Each stop device, as there shown, consists of a light rectangular case *d* within which is pivotally supported a ratchet member *d'* provided with a radial extension formed with a series of notches or steps *d²*. A spring *d³* normally tends to rotate such ratchet member in the 80 direction indicated by the arrow, movement in such direction, however, being limited by a pin *d⁴* which at the same time serves to secure one end of the spring. A locking pawl *d⁵* coöperates with the ratchet teeth 85 on member *d'* to retain the same in whatever position it may be rotated from such normal position in a direction opposite to that indicated by the arrow, such dog being pivoted about an axis *d⁶* and having its rear 90 end *d⁷* extend without the case or in a radial direction with respect to the axis of the drum, which it has been seen carries the whole device in question. A spring *d⁸* normally retains such pawl in its locking position and also retains in retracted position an actuating pawl or dog *d⁹* that is slidably held in the case in position to engage the teeth of the ratchet member when urged forwardly and impart thereto a definite 95 rotational movement.

The pins or plungers *b⁷* carried by levers *b* are designed, when forced inwardly, to enter the corresponding case *d* adjacent to the rear end of this actuating pawl, and by 105 urging the same forwardly to rotate the ratchet member, so as to bring the first of the series of stops, wherewith it is formed, into line with such pin and thus serve as a stop for the same. Said ratchet member 110 will then be retained in this position, despite the retraction of the pin and of the actuating pawl, by means of locking pawl *d⁵*. The normal position of the stop device 115 *D* is that shown in Fig. 3, where member *d'* is held against pin *d⁴* by means of spring *d³*. The effect of the initial operation of the device by the insertion of plunger *b⁷* is to move said member into the position shown in Fig. 4, in which position it remains pending the engagement of the plunger with the first of the stops *d²*, as shown in Fig. 5. Such position of parts moreover is maintained until a plunger *b⁷* is again inserted in the case, upon a subsequent oscillation of 120 the lever bearing such plunger in conjunction with the particular designation, wherewith the particular device *D* in question corresponds. Successive operations of the device *D* serve to bring one stop *d²* after the 125 130

other into position to be engaged by the plunger. Depending upon which stop is thus interposed in the path of the plunger, it will be seen that, if the latter is given its full inward movement, a longitudinal shifting of the drum or platen must result. This shifting is resisted by a spring b^9 or other like means conveniently mounted, as shown, at the farther end of the drum shaft, so that the drum is always returned to its forward position upon conclusion of the operation just described. In order to permit such longitudinal shifting of the drum while still securing the same rotatably to the shaft b^3 , the latter is provided with a collar b^{10} bearing radial arms b^{11} to the outer ends of which arms are in turn secured longitudinally extending pins b^{12} that engage with apertures in the end of the drum, as will be readily understood.

In the normal forward position of the drum the time printing device C is designed to be held by the shaft c' that controls its movement, so as to print just within the margin of the space appropriated to the particular period of time, as for instance, the third day of the week, over which such device is in general located. The effect then of the successive longitudinal shifting of the drum is to cause each successive imprint made during the time thus appropriated, or in other words, during the day in question to come farther and farther to the right of the margin, and thus prevent one impression being made directly over a preceding one. The number of successive records that can be thus made without being superposed will correspond, of course, with the number of stops d^2 on ratchet members d' in the adjustable stop devices D, but the number of these stops can be obviously made smaller or larger than indicated in the illustrative construction shown in the drawings.

In order to restore the stop devices D to their normal position, as is desirable upon entering upon each successive period of time, viz., at the beginning of each day in the case in hand, a lever E pivotally hung in the lower portion of the case A is adapted to be pressed against the outer faces of the several devices so as to engage with the projecting rear ends d^7 of the locking pawls d^8 of said devices. The effect of this engagement is obviously to allow the several ratchet members to fly back into their normal positions under the action of springs d^3 , whereupon said devices are ready for a further series of operations. The setting lever just described, is conveniently carried by a short shaft e mounted in the front wall of the case and provided with a suitable operating means, not shown.

Obviously the adjustable stop device may take on various forms; thus in Fig. 6, we show in place of a pivoted ratchet member,

a longitudinally slidable member d^{11} , which is adapted to engage a plunger b^7 at different points during the latter's inward movement. A locking pawl d^{12} as before serves to hold this member d^{11} against movement under the action of a spring d^{13} connected with a pinion d^{14} that meshes with rack-teeth d^{15} on said member. An actuating pawl d^{16} , corresponding with pawl d^4 of the first-described device, lies in the path of plunger b^4 , so as to be reciprocated thereby, and is adapted to rotate pinion d^{14} by regular amounts to similarly advanced member d^{11} .

Other modes of applying the principle of our invention may be employed instead of the one explained, change being made as regards the mechanism herein disclosed, provided the means stated by any of the following claims or the equivalent of such stated means be employed.

We therefore particularly point out and distinctly claim as our invention:—

1. In a time recorder, the combination of a platen in the form of a rotatable drum; a time-printing device movable longitudinally of said drum; time-controlled means for effecting such movement; a longitudinally reciprocable shaft axially disposed within said drum and connected to actuate said time-printing device to print; a lever operatively connected with said drum and shaft, said lever being rotatable about the axis of said drum to rotate the latter and oscillatory in a plane parallel with such axis to reciprocate said shaft, the connections between said lever and drum rotating the latter in a direction the reverse of that of the former, whereby said drum and lever may be brought into different relative positions; and means operable upon oscillation of said shaft to shift said drum longitudinally.

2. In a time recorder, the combination of a platen in the form of a rotatable drum; a time-printing device movable longitudinally of said drum; time controlled means for effecting such movement; a longitudinally reciprocable shaft axially disposed within said drum and connected to actuate said time-printing device to print; a lever operatively connected with said drum and shaft, said lever being rotatable about the axis of said drum to rotate the latter and oscillatory in a plane parallel with such axis to reciprocate said shaft, the connections between said lever and drum rotating the latter in a manner different from the rotation of the former, whereby said drum and lever may be brought into different relative positions; and means operable upon oscillation of said shaft to shift said drum longitudinally, said means being variously thus operable in different relative positions of said lever and drum.

3. In a time recorder, the combination of

a platen in the form of a rotatable drum; a time-printing device movable longitudinally of said drum; time-controlled means for effecting such movement; a longitudinally reciprocable shaft axially disposed within said drum and connected to actuate said time-printing device to print; a lever operatively connected with said drum and shaft, said lever being rotatable about the axis of said drum to rotate the latter and oscillatory in a plane parallel with such axis to reciprocate said shaft, the connections between said lever and drum rotating the latter in a direction the reverse of that of the former, whereby said drum and lever may be brought into different relative positions; and means operable upon oscillation of said shaft to shift said drum longitudinally, said means being variously thus operable in different relative positions of said lever and drum.

4. In a time recorder the combination of a platen in the form of a rotatable and longitudinally movable drum; a time printing device movable longitudinally of said drum; time controlled means for effecting such movement; a longitudinally reciprocable shaft axially disposed within said drum and connected to actuate said time printing device to print; a lever operatively connected with said drum and said shaft, said lever being rotatable about the axis of said drum to rotate the latter, and oscillatory in a plane parallel with such axis to reciprocate said shaft, operative connections between said lever and said drum whereby the rotation of the former causes rotation of the latter in the reverse direction, thereby bringing said drum and said lever into different relative position, and means oper-

able upon the oscillation of said shaft to shift said drum longitudinally.

5. In a time recorder the combination of a case, a platen in the form of a drum rotatably mounted in said case; a time printing device movable longitudinally of said drum; time controlled means for effecting such movement, said means consisting of a clock mechanism, a rotatable shaft adapted to be rotated by said clock mechanism, stops mounted on said shaft at certain intervals, the rotation of said shaft releasing said time printing device and allowing the same to move along said shaft the distance between two stops; a longitudinally reciprocable shaft axially disposed within said drum and connected to actuate said time printing device to print; a lever operatively connected with said drum and said shaft, said lever being rotatable about the axis of said drum to rotate the latter, and oscillatory in a plane parallel with such axis to reciprocate said shaft; operative connections between said lever and said drum whereby rotation of one is in the reverse direction to that of the other, thereby bringing said drum and said lever into different relative positions.
